S. L. GOLDMAN

SIPHON NOZZLE

Filed Aug. 27, 1921

Inventor:

Sigmund L. Goldman,
Bydgoszcz, Poland,
Attys.

UNITED STATES PATENT OFFICE.

SIGMUND L. GOLDMAN, OF CHICAGO, ILLINOIS.

SIPHON NOZZLE.

Application filed August 27, 1921. Serial No. 496,071.

To all whom it may concern:

Be it known that I, SIGMUND L. GOLDMAN, a citizen of the United States, residing at 147 West Austin Avenue, Chicago, in the county of Cook and State of Illinois, have invented a new and useful Improvement in Siphon Nozzles, of which the following is a specification.

The present invention relates to improvements in siphon nozzles and will be fully understood from the following description, illustrated by the accompanying drawings, in which:

Fig. 1 is a longitudinal sectional view through the nozzle with the parts in position for priming;

Fig. 2 is a longitudinal sectional view through the nozzle with the parts in proper position to hold the siphon after the nozzle has been primed; and

Fig. 3 is a longitudinal sectional view through the device with the parts in position for filling or discharge.

Referring more particularly to the drawings, the numeral 5 indicates the body of the siphon nozzle, which may suitably be formed as an integral casting. This body member has a longitudinal cylindrical portion, through which a longitudinal bore 6 passes and it also has two lateral projections 7 and 8, each of which has a bore communicating with a central bore 6. One of these projections, indicated as 7, communicates with the central bore 6 at a higher point than the other, indicated as 8, which may suitably be curved upwards and outwards. The projection or nipple 7 is employed for priming and to the projection 8 is attached a hose 9 and forms a conduit leading into the nozzle.

Two plungers 10 and 11 are fitted in the bore 6 and are slidably secured therein by means of set screws 12 and 13 respectively, the ends of which enter longitudinal slots in the plungers. The upper plunger 10, the inner end of which is closed, is provided with a projection 14 preferably of cylindrical form, adapted to enter and close a short longitudinal bore or chamber 15 in the upper end of the lower plunger 11. This short bore or chamber 15 is closed off by a partition or plug 16 from a longer longitudinal bore 17 which extends downwardly to substantially the end of the plunger 11.

An angular kerf 18 provides an exit from the bore 17, although any other form of opening may be employed. An opening 19 is drilled through the wall of the plunger 11 above the partition or plug 16, affording communication with the bore or chamber 15 and an opening 20 is bored through the wall of the plunger 11 below the partition or plug 16 affording communication with the bore 17.

After the conduit, or tube, 9, from the vessel to be emptied, is attached to the projecting member 8, the plunger 10 is moved upwardly and plunger 11 downwardly, to the positions shown in Fig. 1, plunger 11, being pulled down by the operator if it fits the body 5 so snugly as not to drop by gravity to lowered position and plunger 10 being held up by the operator if it fits body with such looseness that it would drop by gravity. It is preferred that these plungers fit the body 5 sufficiently tightly that they will not drop by gravity but will require the exertion of slight force against them to move them in either direction. In this position of the parts the siphon nozzle may be filled by suction exerted on the primer 7 which, in practice, would probably be effected by the operator sucking upon the tube 7, the tube 9 communicating with the bore of the projection 8 and this bore, in turn, communicating through the opening 19 with the upper short bore, or chamber 15 in plunger 11, the other end of which is open and communicates freely with the bore of the primer 7. When the nozzle has been filled the operator pushes plunger 10 down and closes the upper end of bore, or chamber 15, of the plunger 11 thereby closing bore 15 to the primer 7 and maintaining the siphon. The position of the parts at this time is indicated in Fig. 2. If it is now desired to fill a bottle or other receptacle the operator, grasping the device at the body 5, inserts the end of the plunger 11 into the neck of the bottle, the latter engaging the shoulder 21 formed on the plunger 11, and by pressing down on the body 5 the latter descends until it engages the shoulder 21, the bore or chamber 15 remaining closed and filled with liquid in this operation.

In thus operating the device the bore 8 moves downwardly to a position in which it communicates with the opening 20 and the liquid thereupon

siphons freely through the projection 8, the opening 20, the bore 17 and the opening or kerf 18, into the bottle or receptacle to be filled. When it has been filled, the siphon 5 nozzle is removed from the bottle, or receptacle, and the parts of the device restored to the position shown in Fig. 2 to arrest the flow of liquid from the device and maintain the siphon, the bore 8 again communicating 10 through opening 19 with the bore 15. As the bore 15 has been retained full of liquid the siphon is unbroken. With the parts constructed as stated above to be preferable, the operator, to restore the parts to the 15 position shown in Fig. 2 would press downwardly on the plunger 10 while raising the body 5, in order that the plunger 10 and 11 maintain the positions relative to each other as shown in this figure.

20 It will be noted that any liquid in priming nozzle 7 which has been in contact with the mouth of the operator may be discarded without affecting the siphon and thus the device is rendered highly sanitary.

25 Although the present invention has been described in connection with the specific details of an embodiment thereon, it is not intended that these details shall be regarded as limitations upon the scope of the invention, except in so far as included in the accompanying claims.

I claim:

1. In a siphon nozzle, a conduit for the introduction of liquid, the nozzle having a bore intersecting the conduit, a member in the bore, said member having a plurality of chambers each provided with an opening, the member being movable to bring the opening of one or another of said chambers 35 into communication with the conduit, and means for closing and opening one of said chambers, said means being movable from a position in which said last-named chamber is open into a position in which said chamber is closed while the latter is in communication with said conduit.

2. In a siphon nozzle, a conduit for the introduction of liquid, the nozzle having a bore intersecting the conduit, a member in the bore, said member having a plurality of chambers each provided with an opening, the member being movable to bring the opening of one or another of said chambers into communication with the conduit, a suction 50 nipple having an opening communicating with one of said chambers in one position of the movable member, and means for closing or opening said chamber.

3. In a siphon nozzle, a conduit for the introduction of liquid, the nozzle having a bore intersecting the conduit, a plunger in the bore, said plunger having separated upper and lower chambers, the latter opening externally of the nozzle, and the plunger being reciprocable to bring one or the other 60

of said chambers into communication with the conduit, and means for closing and opening the upper chamber, said means being movable from a position in which said upper chamber is open into a position in which the latter is closed while this chamber is in communication with said conduit. 70

4. In a siphon nozzle, a conduit for the introduction of liquid, the nozzle having a bore intersecting the conduit, a plunger in the bore, said plunger having separated upper and lower chambers, the latter opening externally of the nozzle, and the plunger being reciprocable to bring one or the other of said chambers into communication with the conduit, a suction nipple opening into the bore of the nozzle above the opening of the conduit thereinto, and means for closing the upper chamber of the plunger. 75

5. In a siphon nozzle, a conduit for the introduction of liquid, the nozzle having a bore intersecting the conduit, a plunger in the bore, said plunger having separated upper and lower chambers, the latter opening externally of the nozzle, and the plunger being reciprocable to bring one or the other of said chambers into communication with the conduit, a suction nipple opening into the bore of the nozzle above the opening of the conduit thereinto, and means for closing the upper chamber of the plunger and simultaneously cutting off the priming nipple from the bore. 80

6. In a siphon nozzle, a conduit for the introduction of liquid, the nozzle having a bore intersecting the conduit, a plunger in the bore, said plunger having separated upper and lower chambers, the latter opening externally of the nozzle and the plunger being reciprocable to bring one or the other of said chambers into communication with the conduit, and a second plunger reciprocable in the bore above the first-mentioned plunger for closing and opening the upper chamber therein. 95

7. In a siphon nozzle, a conduit for the introduction of liquid, the nozzle having a bore intersecting the conduit, a plunger in the bore, said plunger having separated upper and lower chambers, the latter opening externally of the nozzle and the plunger being reciprocable to bring one or the other of said chambers into communication with the conduit, a suction nipple opening into the bore of the nozzle and a second plunger reciprocable in the bore above the first-mentioned plunger for closing and opening the upper chamber therein. 110

8. In a siphon nozzle, a conduit for the introduction of liquid, the nozzle having a bore intersecting the conduit, a plunger in the bore, said plunger having separated upper and lower chambers, the latter opening externally of the nozzle and the plunger being reciprocable to bring one or the other 115

120

130

of said chamber into communication with the conduit, a suction nipple opening into the bore of the nozzle, its opening being above said plunger when the upper chamber is in communication with the conduit, and a second plunger reciprocable in the bore above the first mentioned plunger for closing and opening the upper chamber

therein, said second plunger cutting off the priming nipple when the upper chamber communicates with the conduit and the first-mentioned plunger cutting off the priming nipple when the lower chamber communicates with the conduit.

SIGMUND L. GOLDMAN.
